MULTILAYER COIL COMPONENT

TECHNICAL FIELD

The present invention relates to a multilayer coil component.

BACKGROUND

Patent Literature 1 (Japanese Unexamined Patent Publication No. 2013-38263) discloses a multilayer coil component including a component main body (element body) and one coil disposed in the component main body and configured by a plurality of conductor portions.

SUMMARY

An object of one aspect of the present invention is to provide a multilayer coil component capable of reducing electrical resistivity.

A multilayer coil component according to one aspect of the present invention includes: an element body formed by stacking a magnetic body layer containing a plurality of metal magnetic particles of a soft magnetic material; a first coil disposed in the element body and configured to include a plurality of first coil conductors; a second coil disposed in the element body and configured to include a plurality of second coil conductors; a first external electrode to which one end portion of each of the first coil and the second coil is connected; and a second external electrode to which the other end portion of each of the first coil and the second coil is connected.

In the multilayer coil component according to one aspect of the present invention, the first coil and the second coil are disposed in the element body. One end portion of each of the first coil and the second coil is connected to the first external electrode, and the other end portion of each of the first coil and the second coil is connected to the second external electrode. As a result, the multilayer coil component has a configuration in which the first coil and the second coil are connected in parallel. Accordingly, in the multilayer coil component, at least two current flow paths can be ensured as compared with a configuration in which one coil is disposed in the element body, and thus the electrical resistivity of direct current resistance can be reduced. As a result, in the multilayer coil component, the quality factor (Q) value can be increased, and thus characteristics can be improved. In addition, in the multilayer coil component, loss attributable to heat generation can be reduced, and thus quality can be improved.

In the multilayer coil component, the element body is formed by stacking the magnetic body layer containing a plurality of metal magnetic particles of a soft magnetic alloy. As a result, in the multilayer coil component, direct current superimposition characteristics can be improved as compared with an element body formed of a ferrite material.

In one embodiment, the first coil and the second coil may be separated from each other in a stacking direction of the magnetic body layer in the element body and, between the first coil and the second coil of the element body, at least a region where the first coil and the second coil overlap when viewed from the stacking direction may be higher in electrical resistivity than the magnetic body layer. In this configuration, the electrical resistivity between the layers of the first coil and the second coil can be made higher than that of the element body material. As a result, the withstand voltage of the multilayer coil component can be improved.

2

In one embodiment, a high-resistance portion having a width dimension equal to or greater than width dimensions of the first coil conductor and the second coil conductor and higher in electrical resistivity than the magnetic body layer may be disposed in the region where the first coil and the second coil overlap when viewed from the stacking direction. In this configuration, the electrical resistivity between the layers of the first coil and the second coil can be made higher than that of the element body material by the high-resistance portion. As a result, the withstand voltage of the multilayer coil component can be improved.

In one embodiment, a high-resistance layer higher in electrical resistivity than the magnetic body layer may be provided between the first coil and the second coil in the element body. In this configuration, the electrical resistivity between the layers of the first coil and the second coil can be made higher than that of the element body material by the high-resistance layer. As a result, the withstand voltage of the multilayer coil component can be improved.

In one embodiment, a conductor closest to the second coil in the first coil and a conductor closest to the first coil in the second coil may not overlap when viewed from a stacking direction of the magnetic body layer. With this configuration, the withstand voltage of the multilayer coil component can be improved.

In one embodiment, the first coil may have a first connecting conductor connected to the first external electrode and a second connecting conductor connected to the second external electrode, the second coil may have a third connecting conductor connected to the first external electrode and a fourth connecting conductor connected to the second external electrode, a distance between the second connecting conductor and the fourth connecting conductor may be shorter than a distance between the first connecting conductor and the third connecting conductor in a stacking direction of the magnetic body layer, and a winding direction of the first coil and a winding direction of the second coil may be the same when viewed from the stacking direction. In this configuration, by the distance between the second connecting conductor and the fourth connecting conductor being shorter than the distance between the first connecting conductor and the third connecting conductor in the stacking direction of the magnetic body layer, it is possible to reduce the potential difference between the first coil and the second coil when a current flows through the first coil and the second coil. Accordingly, the withstand voltage of the multilayer coil component can be improved. In addition, the winding direction of the first coil and the winding direction of the second coil are the same when viewed from the stacking direction, and thus the orientations of the magnetic fluxes of the first coil and the second coil are the same. As a result, the inductance values of the first coil and the second coil can be made equal.

In one embodiment, the first coil may have a first connecting conductor connected to the first external electrode and a second connecting conductor connected to the second external electrode, the second coil may have a third connecting conductor connected to the first external electrode and a fourth connecting conductor connected to the second external electrode, a distance between the second connecting conductor and the fourth connecting conductor may be shorter than a distance between the first connecting conductor and the third connecting conductor in a stacking direction of the magnetic body layer, and a winding direction of the first coil may be opposite to a winding direction of the second coil when viewed from the stacking direction. In this configuration, the potential difference can be reduced by the

distance between the second connecting conductor and the fourth connecting conductor being shorter than the distance between the first connecting conductor and the third connecting conductor in the stacking direction of the magnetic body layer. Accordingly, the withstand voltage of the multilayer coil component can be improved. In addition, the winding direction of the first coil is opposite to the winding direction of the second coil when viewed from the stacking direction, and thus the magnetic flux generated by the first coil and the magnetic flux generated by the second coil cancel each other out. Accordingly, magnetic saturation can be suppressed, and thus direct current superimposition characteristics can be improved.

In one embodiment, the number of the first coil conductors of the first coil may be the same as the number of the second coil conductors of the second coil. In this configuration, the magnetic flux generated by the first coil and the magnetic flux generated by the second coil can be effectively offset. Accordingly, magnetic saturation can be suppressed more effectively, and thus direct current superimposition characteristics can be improved.

In one embodiment, the two or more metal magnetic particles may be disposed along a stacking direction of the magnetic body layer between the first coil and the second coil. With this configuration, the withstand voltage between the layers of the first coil and the second coil can be improved.

According to one aspect of the present invention, electrical resistivity can be reduced.

BRIEF DESCRIPTION OF THE DRAWINGS

FIG. 1 is a perspective view illustrating a multilayer coil component according to a first embodiment.

FIG. 2 is a diagram illustrating a cross-sectional configuration of the multilayer coil component illustrated in FIG. 1.

FIG. 3 is an exploded perspective view of the multilayer coil component illustrated in FIG. 1.

FIG. 4 is a diagram illustrating a cross-sectional configuration of a multilayer coil component according to a second embodiment.

FIG. 5 is an exploded perspective view of the multilayer coil component illustrated in FIG. 4.

FIG. 6 is a diagram illustrating a cross-sectional configuration of a multilayer coil component according to a third embodiment.

FIG. 7 is an exploded perspective view of the multilayer coil component illustrated in FIG. 6.

FIG. 8 is a diagram illustrating a cross-sectional configuration of a multilayer coil component according to a fourth embodiment.

FIG. 9 is an exploded perspective view of the multilayer coil component illustrated in FIG. 8.

DETAILED DESCRIPTION

Hereinafter, preferred embodiments of the present invention will be described in detail with reference to the accompanying drawings. It should be noted that in the description of the drawings, the same or equivalent elements are denoted by the same reference numerals with redundant description omitted.

First Embodiment

As illustrated in FIG. 1, a multilayer coil component 1 according to a first embodiment includes an element body 2

and a first external electrode 4 and a second external electrode 5 respectively disposed on both end portions of the element body 2.

The element body 2 has a rectangular parallelepiped shape. The rectangular parallelepiped shape includes the shape of a rectangular parallelepiped with chamfered corner and ridge portions and the shape of a rectangular parallelepiped with rounded corner and ridge portions. The element body 2 has, as the outer surfaces thereof, a pair of end surfaces 2a and 2b facing each other, a pair of main surfaces 2c and 2d facing each other, and a pair of side surfaces 2e and 2f facing each other. The facing direction in which the pair of main surfaces 2c and 2d face each other is a first direction D1. The facing direction in which the pair of end surfaces 2a and 2b face each other is a second direction D2. The facing direction in which the pair of side surfaces 2e and 2f face each other is a third direction D3. In the present embodiment, the first direction D1 is the height direction of the element body 2. The second direction D2 is the longitudinal direction of the element body 2 and is orthogonal to the first direction D1. The third direction D3 is the width direction of the element body 2 and is orthogonal to the first direction D1 and the second direction D2.

The pair of end surfaces 2a and 2b extend in the first direction D1 so as to interconnect the pair of main surfaces 2c and 2d. The pair of end surfaces 2a and 2b also extend in the third direction D3 (short side direction of the pair of main surfaces 2c and 2d). The pair of side surfaces 2e and 2f extend in the first direction D1 so as to interconnect the pair of main surfaces 2c and 2d. The pair of side surfaces 2e and 2f also extend in the second direction D2 (long side direction of the pair of end surfaces 2a and 2b). The main surface 2d can be defined as a mounting surface facing another electronic device when the multilayer coil component 1 is mounted on the electronic device (for example, a circuit board or an electronic component).

As illustrated in FIG. 3, the element body 2 is configured by stacking a plurality of magnetic body layers 6 and a magnetic body layer 7. Each magnetic body layer 6 and the magnetic body layer 7 are stacked in the first direction D1. In other words, the first direction D1 is the stacking direction. The element body 2 has the plurality of magnetic body layers 6 and the magnetic body layer 7 that are stacked. In the actual element body 2, the plurality of magnetic body layers 6 and the magnetic body layer 7 are integrated to the extent that the boundary between the layers cannot be visually recognized.

Each magnetic body layer 6 and the magnetic body layer 7 contain a plurality of metal magnetic particles. The metal magnetic particles are configured from a soft magnetic alloy (soft magnetic material). The soft magnetic alloy is, for example, a Fe—Si-based alloy. In a case where the soft magnetic alloy is a Fe—Si-based alloy, the soft magnetic alloy may contain P. The soft magnetic alloy may be, for example, a Fe—Ni—Si—M-based alloy. “M” contains one or more elements selected from Co, Cr, Mn, P, Ti, Zr, Hf, Nb, Ta, Mo, Mg, Ca, Sr, Ba, Zn, B, Al, and rare-earth elements.

The metal magnetic particles are bonded to each other in the magnetic body layer 6 and the magnetic body layer 7. The bond between the metal magnetic particles is realized by, for example, the bond between the oxide films formed on the surfaces of the metal magnetic particles. In the magnetic body layer 6 and the magnetic body layer 7, the metal magnetic particles are electrically insulated from each other by the bond between the oxide films. The thickness of the oxide film is, for example, 5 to 60 nm or less. The oxide film may be configured by one or more layers.

The magnetic body layer 7 contains a material higher in electrical resistivity than each magnetic body layer 6. In the present embodiment, the magnetic body layer 7 contains, for example, ZrO_2 . The magnetic body layer 7 is disposed between the magnetic body layer 6 and the magnetic body layer 6 in the first direction D1. The magnetic body layer 7 is disposed between a first coil 8 and a second coil 9. The magnetic body layer 7 configures a high-resistance layer in the element body 2. It should be noted that a plurality of the magnetic body layers 7 may be included.

The element body 2 contains a resin. The resin is present between the plurality of metal magnetic particles. The resin is an electrically insulating resin (insulating resin). The insulating resin includes, for example, a silicone resin, a phenol resin, an acrylic resin, or an epoxy resin.

The average particle size of the metal magnetic particles is 0.5 to 15 μm . In the present embodiment, the average particle size of the metal magnetic particles is 5 μm . In the present embodiment, the "average particle size" means the particle size at an integrated value of 50% in a particle size distribution obtained by the laser diffraction-scattering method.

As illustrated in FIG. 1, the first external electrode 4 is disposed on the end surface 2a side of the element body 2, and the second external electrode 5 is disposed on the end surface 2b side of the element body 2. In other words, the first external electrode 4 and the second external electrode 5 are positioned apart from each other in the facing direction of the pair of end surfaces 2a and 2b. The first external electrode 4 and the second external electrode 5 contain a conductive material (for example, Ag or Pd). The first external electrode 4 and the second external electrode 5 are configured as sintered bodies of a conductive paste containing a conductive metal powder (for example, Ag powder or Pd powder) and glass frit. By electroplating, plating layers are formed on the surfaces of the first external electrode 4 and the second external electrode 5. Ni, Sn, or the like is used for the electroplating.

The first external electrode 4 is disposed on one end surface 2a side. The first external electrode 4 includes the five electrode parts of a first electrode part 4a positioned on the end surface 2a, a second electrode part 4b positioned on the main surface 2c, a third electrode part 4c positioned on the main surface 2d, a fourth electrode part 4d positioned on the side surface 2e, and a fifth electrode part 4e positioned on the side surface 2f. The first electrode part 4a, the second electrode part 4b, the third electrode part 4c, the fourth electrode part 4d, and the fifth electrode part 4e are connected in the ridge portion of the element body 2 and are electrically interconnected. The first external electrode 4 is formed on the five surfaces of one end surface 2a, the pair of main surfaces 2c and 2d, and the pair of side surfaces 2e and 2f. The first electrode part 4a, the second electrode part 4b, the third electrode part 4c, the fourth electrode part 4d, and the fifth electrode part 4e are integrally formed.

In the present embodiment, the edges (end surfaces) of the second electrode part 4b and the third electrode part 4c of the first external electrode 4 are along, for example, the third direction D3. The edge of the second electrode part 4b is linearly formed on the main surface 2c. The edge of the third electrode part 4c is linearly formed on the main surface 2d. The edges of the fourth electrode part 4d and the fifth electrode part 4e of the first external electrode 4 are along the first direction D1. The edge of the fourth electrode part 4d is linearly formed on the side surface 2e. The edge of the fifth electrode part 4e is linearly formed on the side surface 2f. It should be noted that the shape of the edge of each of

the second electrode part 4b, the third electrode part 4c, the fourth electrode part 4d, and the fifth electrode part 4e may be curved or may be uneven.

The second external electrode 5 is disposed on the other end surface 2b side. The second external electrode 5 includes the five electrode parts of a first electrode part 5a positioned on the end surface 2b, a second electrode part 5b positioned on the main surface 2c, a third electrode part 5c positioned on the main surface 2d, a fourth electrode part 5d positioned on the side surface 2e, and a fifth electrode part 5e positioned on the side surface 2f. The first electrode part 5a and the second electrode part 5b, the third electrode part 5c, the fourth electrode part 5d, and the fifth electrode part 5e are connected in the ridge portion of the element body 2 and are electrically interconnected. The second external electrode 5 is formed on the five surfaces of one end surface 2b, the pair of main surfaces 2c and 2d, and the pair of side surfaces 2e and 2f. The first electrode part 5a, the second electrode part 5b, the third electrode part 5c, the fourth electrode part 5d, and the fifth electrode part 5e are integrally formed.

In the present embodiment, the edges of the second electrode part 5b and the third electrode part 5c of the second external electrode 5 are along, for example, the third direction D3. The edge of the second electrode part 5b is linearly formed on the main surface 2c. The edge of the third electrode part 5c is linearly formed on the main surface 2d. The edges of the fourth electrode part 5d and the fifth electrode part 5e of the second external electrode 5 are along the first direction D1. The edge of the fourth electrode part 5d is linearly formed on the side surface 2e. The edge of the fifth electrode part 5e is linearly formed on the side surface 2f. It should be noted that the shape of the edge of each of the second electrode part 5b, the third electrode part 5c, the fourth electrode part 5d, and the fifth electrode part 5e may be curved or may be uneven.

As for the multilayer coil component 1, the first coil 8 and the second coil 9 are disposed in the element body 2 as illustrated in FIG. 2. The first coil 8 and the second coil 9 are separated in the first direction D1 in the element body 2. In the present embodiment, the first coil 8 is disposed on the main surface 2c side of the element body 2. Specifically, the first coil 8 is disposed in the region that is closer to the main surface 2c side than the middle of the element body 2 in the first direction D1. The second coil 9 is disposed on the main surface 2d side of the element body 2. Specifically, the second coil 9 is disposed in the region that is closer to the main surface 2d side than the middle of the element body 2 in the first direction D1. In the multilayer coil component 1, the first coil 8 and the second coil 9 are electrically connected in parallel.

As illustrated in FIG. 3, the first coil 8 is configured in a spiral shape with a plurality of first coil conductors 20, 21, 22, 23, 24, and 25 and a first connecting conductor 26 and a second connecting conductor 27 electrically connected. The first coil conductor 20 and the first connecting conductor 26 are integrally formed. The adjacent first coil conductors 20, 21, 22, 23, 24, and 25 are electrically connected by a through hole conductor (not illustrated). The first coil conductor 25 and the second connecting conductor 27 are electrically connected by a through hole conductor (not illustrated). The first connecting conductor 26 configures one end portion of the first coil 8. The first connecting conductor 26 is exposed on the end surface 2a of the element body 2 and is connected to the first external electrode 4 (first electrode part 4a). The second connecting conductor 27 configures the other end portion of the first coil 8. The

second connecting conductor 27 is exposed on the end surface 2b of the element body 2 and is connected to the second external electrode 5 (first electrode part 5a).

The second coil 9 is configured in a spiral shape with a plurality of second coil conductors 30, 31, 32, 33, 34, and 35 and a third connecting conductor 36 and a fourth connecting conductor 37 electrically connected. The second coil conductor 30 and the third connecting conductor 36 are integrally formed. The adjacent second coil conductors 30, 31, 32, 33, 34, and 35 are electrically connected by a through hole conductor (not illustrated). The second coil conductor 35 and the fourth connecting conductor 37 are electrically connected by a through hole conductor (not illustrated). The third connecting conductor 36 configures one end portion of the second coil 9. The third connecting conductor 36 is exposed on the end surface 2a of the element body 2 and is connected to the first external electrode 4 (first electrode part 4a). The fourth connecting conductor 37 configures the other end portion of the second coil 9. The fourth connecting conductor 37 is exposed on the end surface 2b of the element body 2 and is connected to the second external electrode 5 (first electrode part 5a).

The first coil conductors 20, 21, 22, 23, 24, and 25, the first connecting conductor 26, the second connecting conductor 27, the second coil conductors 30, 31, 32, 33, 34, and 35, the third connecting conductor 36, and the fourth connecting conductor 37 are made of a conductive material usually used as a conductor of a coil (for example, Ni or Cu). The first coil conductors 20, 21, 22, 23, 24, and 25, the first connecting conductor 26, the second connecting conductor 27, the second coil conductors 30, 31, 32, 33, 34, and 35, the third connecting conductor 36, and the fourth connecting conductor 37 are configured as a sintered body of a conductive paste containing the above conductive material.

As illustrated in FIG. 2, between the first coil 8 and the second coil 9 of the element body 2 in the multilayer coil component 1, at least the region where the first coil 8 and the second coil 9 overlap when viewed from the first direction D1 is higher in electrical resistivity than the magnetic body layer 6. In the present embodiment, the magnetic body layer 7 (high-resistance layer) higher in electrical resistivity than the magnetic body layer 6 configuring most of the element body 2 is provided between the first coil 8 and the second coil 9 in the element body 2.

Between the first coil 8 and the second coil 9, two or more metal magnetic particles are disposed along the first direction D1. The metal magnetic particles are lined up along the first direction D1. The metal magnetic particles being lined up along the first direction D1 includes not only a state where the entire metal magnetic particles overlap when viewed from the first direction D1 but also a state where the metal magnetic particles overlap at least in part when viewed from the first direction D1.

In the multilayer coil component 1, a distance H1 between the first connecting conductor 26 of the first coil 8 and the third connecting conductor 36 of the second coil 9 is the same as a distance H2 between the second connecting conductor 27 of the first coil 8 and the fourth connecting conductor 37 of the second coil 9. The winding direction of the first coil 8 and the winding direction of the second coil 9 are the same. As a result, when a current flows through the multilayer coil component 1, the orientation of the magnetic flux generated in the first coil 8 and the orientation of the magnetic flux generated in the second coil 9 become the same.

In the multilayer coil component 1, the conductor that is closest to the second coil 9 in the first coil 8 and the

conductor that is closest to the first coil 8 in the second coil 9 do not overlap when viewed from the first direction D1. Specifically, the second connecting conductor 27 of the first coil 8 and the second coil conductor 30 and the third connecting conductor 36 of the second coil 9 do not overlap when viewed from the first direction D1.

As described above, in the multilayer coil component 1 according to the present embodiment, the first coil 8 and the second coil 9 are disposed in the element body 2. One end portion of each of the first coil 8 and the second coil 9 is connected to the first external electrode 4, and the other end portion of each of the first coil 8 and the second coil 9 is connected to the second external electrode 5. As a result, the multilayer coil component 1 has a configuration in which the first coil 8 and the second coil 9 are connected in parallel. Accordingly, in the multilayer coil component 1, at least two current flow paths can be ensured as compared with a configuration in which one coil is disposed in the element body 2, and thus the electrical resistivity of direct current resistance can be reduced. As a result, in the multilayer coil component 1, the quality factor (Q) value can be increased, and thus characteristics can be improved. In addition, in the multilayer coil component 1, loss attributable to heat generation can be reduced, and thus quality can be improved.

In the multilayer coil component 1, the element body 2 is formed by stacking the magnetic body layer 6 containing a plurality of metal magnetic particles of a soft magnetic alloy. As a result, in the multilayer coil component 1, direct current superimposition characteristics can be improved as compared with an element body formed of a ferrite material.

In the multilayer coil component 1 according to the present embodiment, the first coil 8 and the second coil 9 are separated from each other in the stacking direction of the magnetic body layer 6 in the element body 2. Between the first coil 8 and the second coil 9 of the element body 2, at least the region where the first coil 8 and the second coil 9 overlap when viewed from the first direction D1 is higher in electrical resistivity than the magnetic body layer 6. Specifically, in the element body 2, the magnetic body layer 7 (high-resistance layer) higher in electrical resistivity than the magnetic body layer 6 is provided between the first coil 8 and the second coil 9. In this configuration, the electrical resistivity between the layers of the first coil 8 and the second coil 9 can be made higher than that of the element body material by the magnetic body layer 7. As a result, the withstand voltage of the multilayer coil component 1 can be improved.

In the multilayer coil component 1 according to the present embodiment, the winding direction of the first coil 8 and the winding direction of the second coil 9 are the same. As a result, when a current flows through the multilayer coil component 1, the orientation of the magnetic flux generated in the first coil 8 and the orientation of the magnetic flux generated in the second coil 9 become the same. Accordingly, in the multilayer coil component 1, the inductance values of the first coil 8 and the second coil 9 can be made the same.

In the multilayer coil component 1 according to the present embodiment, the conductor that is closest to the second coil 9 in the first coil 8 and the conductor that is closest to the first coil 8 in the second coil 9 do not overlap when viewed from the first direction D1. Specifically, the second connecting conductor 27 of the first coil 8 and the second coil conductor 30 and the third connecting conductor 36 of the second coil 9 do not overlap when viewed from the first direction D1. With this configuration, the withstand voltage of the multilayer coil component 1 can be improved.

In the multilayer coil component 1 according to the present embodiment, two or more metal magnetic particles are disposed along the first direction D1 between the first coil 8 and the second coil 9. With this configuration, the withstand voltage of the multilayer coil component 1 can be improved.

Second Embodiment

Next, a second embodiment will be described. As illustrated in FIG. 4, a multilayer coil component 1A according to the second embodiment includes an element body 2A and the first external electrode 4 and the second external electrode 5 respectively disposed on both end portions of the element body 2A.

As illustrated in FIG. 5, the element body 2A is configured by stacking the plurality of magnetic body layers 6. Each magnetic body layer 6 is stacked in the first direction D1. In other words, the first direction D1 is the stacking direction. The element body 2A has the plurality of magnetic body layers 6 that are stacked. In the actual element body 2A, the plurality of magnetic body layers 6 are integrated to the extent that the boundary between the layers cannot be visually recognized.

As for the multilayer coil component 1A, the first coil 8 and the second coil 9 are disposed in the element body 2 as illustrated in FIG. 4. The first coil 8 and the second coil 9 are separated in the first direction D1 in the element body 2.

The multilayer coil component 1A has a high-resistance portion 40 disposed in the element body 2. The high-resistance portion 40 is disposed in the region where the first coil 8 and the second coil 9 overlap when viewed from the first direction D1. In the present embodiment, the high-resistance portion 40 has a frame shape. The width dimension of the high-resistance portion 40 is equal to or greater than the width dimensions of the first coil conductors 20, 21, 22, 23, 24, and 25 and the second coil conductors 30, 31, 32, 33, 34, and 35. The high-resistance portion 40 is higher in electrical resistivity than the magnetic body layer 6 of the element body 2. The high-resistance portion 40 is formed of, for example, ZrO₂. The high-resistance portion 40 is not limited to the frame shape and may be, for example, rectangular. In a case where the high-resistance portion 40 is rectangular, the outer edge of the high-resistance portion 40 covers the outer edges of the first coil conductors 20, 21, 22, 23, 24, and 25 and the second coil conductors 30, 31, 32, 33, 34, and 35 when viewed from the first direction D1.

As described above, in the multilayer coil component 1A according to the present embodiment, the first coil 8 and the second coil 9 are disposed in the element body 2A. Accordingly, in the multilayer coil component 1A, the electrical resistivity of direct current resistance can be reduced.

In the multilayer coil component 1A according to the present embodiment, the high-resistance portion 40 having a width dimension equal to or greater than the width dimensions of the first coil conductors 20, 21, 22, 23, 24, and 25 and the second coil conductors 30, 31, 32, 33, 34, and 35 and higher in electrical resistivity than the magnetic body layer 6 is disposed in the region where the first coil 8 and the second coil 9 overlap when viewed from the first direction D1. In this configuration, the electrical resistivity between the layers of the first coil 8 and the second coil 9 can be made higher than that of the element body material by the high-resistance portion 40. As a result, the withstand voltage of the multilayer coil component 1A can be improved.

A form in which the high-resistance portion 40 is formed of ZrO₂ in the multilayer coil component 1A has been

described as an example. However, the high-resistance portion 40 may be a void. In a case where the high-resistance portion 40 is a void, a green sheet to become the magnetic body layer 6 is formed, and a through portion is formed by laser machining at the position on the green sheet where the high-resistance portion 40 (void) is to be formed. Subsequently, the through portion is filled with a resin that disappears when a green sheet-stacked green chip is fired. By firing the green chip, the resin disappears and the void is formed.

Third Embodiment

Next, a third embodiment will be described. As illustrated in FIG. 6, a multilayer coil component 1B according to the third embodiment includes an element body 2B and the first external electrode 4 and the second external electrode 5 respectively disposed on both end portions of the element body 2B.

As illustrated in FIG. 7, the element body 2B is configured by stacking the plurality of magnetic body layers 6. Each magnetic body layer 6 is stacked in the first direction D1. In other words, the first direction D1 is the stacking direction. The element body 2B has the plurality of magnetic body layers 6 that are stacked. In the actual element body 2B, the plurality of magnetic body layers 6 are integrated to the extent that the boundary between the layers cannot be visually recognized.

As for the multilayer coil component 1B, the first coil 8 and a second coil 9B are disposed in the element body 2B as illustrated in FIG. 6. The first coil 8 and the second coil 9B are separated in the first direction D1 in the element body 2B. In the present embodiment, the first coil 8 is disposed on the main surface 2c side of the element body 2B. Specifically, the first coil 8 is disposed in the region that is closer to the main surface 2c side than the middle of the element body 2B in the first direction D1. The second coil 9B is disposed on the main surface 2d side of the element body 2B. Specifically, the second coil 9B is disposed in the region that is closer to the main surface 2d side than the middle of the element body 2B in the first direction D1. In the multilayer coil component 1, the first coil 8 and the second coil 9B are electrically connected in parallel.

As illustrated in FIG. 7, the first coil 8 is configured in a spiral shape with the plurality of first coil conductors 20, 21, 22, 23, 24, and 25 and the first connecting conductor 26 and the second connecting conductor 27 electrically connected. The first coil conductor 20 and the first connecting conductor 26 are integrally formed. The adjacent first coil conductors 20, 21, 22, 23, 24, and 25 are electrically connected by a through hole conductor (not illustrated). The first coil conductor 25 and the second connecting conductor 27 are electrically connected by a through hole conductor (not illustrated). The first connecting conductor 26 configures one end portion of the first coil 8. The first connecting conductor 26 is exposed on the end surface 2a of the element body 2 and is connected to the first external electrode 4 (first electrode part 4a). The second connecting conductor 27 configures the other end portion of the first coil 8. The second connecting conductor 27 is exposed on the end surface 2b of the element body 2 and is connected to the second external electrode 5 (first electrode part 5a).

The second coil 9B is configured in a spiral shape with a plurality of second coil conductors 50, 51, 52, 53, 54, and 55 and a third connecting conductor 56 and a fourth connecting conductor 57 electrically connected. The second coil conductor 55 and the third connecting conductor 56 are inte-

grally formed. The adjacent second coil conductors **50**, **51**, **52**, **53**, **54**, and **55** are electrically connected by a through hole conductor (not illustrated). The second coil conductor **50** and the fourth connecting conductor **57** are electrically connected by a through hole conductor (not illustrated). The third connecting conductor **56** configures one end portion of the second coil **9B**. The third connecting conductor **56** is exposed on the end surface **2a** of the element body **2B** and is connected to the first external electrode **4** (first electrode part **4a**). The fourth connecting conductor **57** configures the other end portion of the second coil **9B**. The fourth connecting conductor **57** is exposed on the end surface **2b** of the element body **2B** and is connected to the second external electrode **5** (first electrode part **5a**).

As illustrated in FIG. 6, in the multilayer coil component **1B**, the distance **H1** between the first connecting conductor **26** of the first coil **8** and the third connecting conductor **56** of the second coil **9B** is longer than the distance **H2** between the second connecting conductor **27** of the first coil **8** and the fourth connecting conductor **57** of the second coil **9B**. In other words, the distance **H2** between the second connecting conductor **27** of the first coil **8** and the fourth connecting conductor **57** of the second coil **9B** is shorter than the distance **H1** between the first connecting conductor **26** of the first coil **8** and the third connecting conductor **56** of the second coil **9B**. The winding direction of the first coil **8** and the winding direction of the second coil **9B** are the same. As a result, when a current flows through the multilayer coil component **1**, the orientation of the magnetic flux generated in the first coil **8** and the orientation of the magnetic flux generated in the second coil **9** become the same.

As described above, in the multilayer coil component **1B** according to the present embodiment, the first coil **8** and the second coil **9B** are disposed in the element body **2B**. Accordingly, in the multilayer coil component **1B**, the electrical resistivity of direct current resistance can be reduced.

In the multilayer coil component **1B** according to the present embodiment, in the first direction **D1**, the distance **H2** between the second connecting conductor **27** of the first coil **8** and the fourth connecting conductor **57** of the second coil **9B** is shorter than the distance **H1** between the first connecting conductor **26** of the first coil **8** and the third connecting conductor **56** of the second coil **9B**. In this configuration, by the distance **H2** between the second connecting conductor **27** of the first coil **8** and the fourth connecting conductor **57** of the second coil **9B** being shorter than the distance **H1** between the first connecting conductor **26** of the first coil **8** and the third connecting conductor **56** of the second coil **9B**, it is possible to reduce the potential difference between the first coil **8** and the second coil **9B** when a current flows through the first coil **8** and the second coil **9B**. Accordingly, the withstand voltage of the multilayer coil component **1B** can be improved.

In the multilayer coil component **1B** according to the present embodiment, the winding direction of the first coil **8** and the winding direction of the second coil **9B** are the same when viewed from the first direction **D1**. In this configuration, the orientations of the magnetic fluxes of the first coil **8** and the second coil **9B** are the same. As a result, the inductance values of the first coil **8** and the second coil **9B** can be made equal.

In the multilayer coil component **1B**, the element body **2B** may have the magnetic body layer **7** (high-resistance layer) as in the case of the multilayer coil component **1** or the high-resistance portion **40** may be disposed in the element body **2B** as in the case of the multilayer coil component **1A**.

Next, a fourth embodiment will be described. As illustrated in FIG. 8, a multilayer coil component **1C** according to the fourth embodiment includes an element body **2C** and the first external electrode **4** and the second external electrode **5** respectively disposed on both end portions of the element body **2C**.

As illustrated in FIG. 9, the element body **2C** is configured by stacking the plurality of magnetic body layers **6**. Each magnetic body layer **6** is stacked in the first direction **D1**. In other words, the first direction **D1** is the stacking direction. The element body **2C** has the plurality of magnetic body layers **6** that are stacked. In the actual element body **2C**, the plurality of magnetic body layers **6** are integrated to the extent that the boundary between the layers cannot be visually recognized.

As for the multilayer coil component **1C**, a first coil **8C** and a second coil **9C** are disposed in the element body **2C** as illustrated in FIG. 8. The first coil **8C** and the second coil **9C** are separated in the first direction **D1** in the element body **2C**. In the present embodiment, the first coil **8** is disposed on the main surface **2c** side of the element body **2C**. Specifically, the first coil **8C** is disposed in the region that is closer to the main surface **2c** side than the middle of the element body **2C** in the first direction **D1**. The second coil **9B** is disposed on the main surface **2d** side of the element body **2C**. Specifically, the second coil **9B** is disposed in the region that is closer to the main surface **2d** side than the middle of the element body **2C** in the first direction **D1**. In the multilayer coil component **1C**, the first coil **8C** and the second coil **9C** are electrically connected in parallel.

As illustrated in FIG. 9, the first coil **8C** is configured by electrically connecting a plurality of first coil conductors **60**, **61**, **62**, **63**, **64**, and **65** and a first connecting conductor **66** and a second connecting conductor **67**. The first coil conductor **60** and the first connecting conductor **66** are integrally formed. The adjacent first coil conductors **60**, **61**, **62**, **63**, **64**, and **65** are electrically connected by a through hole conductor (not illustrated). The first coil conductor **65** and the second connecting conductor **67** are electrically connected by a through hole conductor (not illustrated). The first connecting conductor **66** configures one end portion of the first coil **8C**. The first connecting conductor **66** is exposed on the end surface **2a** of the element body **2C** and is connected to the first external electrode **4** (first electrode part **4a**). The second connecting conductor **67** configures the other end portion of the first coil **8C**. The second connecting conductor **67** is exposed on the end surface **2b** of the element body **2C** and is connected to the second external electrode **5** (first electrode part **5a**).

The second coil **9C** is configured by electrically connecting a plurality of second coil conductors **70**, **71**, **72**, **73**, **74**, and **75** and a third connecting conductor **76** and a fourth connecting conductor **77**. The second coil conductor **75** and the third connecting conductor **76** are integrally formed. The adjacent second coil conductors **70**, **71**, **72**, **73**, **74**, and **75** are electrically connected by a through hole conductor (not illustrated). The second coil conductor **70** and the fourth connecting conductor **77** are electrically connected by a through hole conductor (not illustrated). The third connecting conductor **76** configures one end portion of the second coil **9C**. The third connecting conductor **76** is exposed on the end surface **2a** of the element body **2C** and is connected to the first external electrode **4** (first electrode part **4a**). The fourth connecting conductor **77** configures the other end portion of the second coil **9C**. The fourth connecting con-

13

ductor 77 is exposed on the end surface 2b of the element body 2C and is connected to the second external electrode 5 (first electrode part 5a).

As illustrated in FIG. 8, in the multilayer coil component 1C, the distance H1 between the first connecting conductor 66 of the first coil 8C and the third connecting conductor 76 of the second coil 9C is longer than the distance H2 between the second connecting conductor 67 of the first coil 8C and the fourth connecting conductor 77 of the second coil 9C. In other words, the distance H2 between the second connecting conductor 67 of the first coil 8C and the fourth connecting conductor 77 of the second coil 9C is shorter than the distance H1 between the first connecting conductor 66 of the first coil 8C and the third connecting conductor 76 of the second coil 9C. The winding direction of the first coil 8C and the winding direction of the second coil 9C are opposite (reverse). As a result, when a current flows through the multilayer coil component 1C, the magnetic flux generated in the first coil 8 and the magnetic flux generated in the second coil 9 cancel each other out (offset).

As described above, in the multilayer coil component 1C according to the present embodiment, the first coil 8C and the second coil 9C are disposed in the element body 2C. Accordingly, in the multilayer coil component 1C, the electrical resistivity of direct current resistance can be reduced.

In the multilayer coil component 1C according to the present embodiment, in the first direction D1, the distance H2 between the second connecting conductor 67 of the first coil 8C and the fourth connecting conductor 77 of the second coil 9B is shorter than the distance H1 between the first connecting conductor 66 of the first coil 8C and the third connecting conductor 76 of the second coil 9C. In this configuration, by the distance H2 between the second connecting conductor 67 of the first coil 8C and the fourth connecting conductor 77 of the second coil 9C being shorter than the distance H1 between the first connecting conductor 66 of the first coil 8C and the third connecting conductor 76 of the second coil 9C, it is possible to reduce the potential difference between the first coil 8C and the second coil 9C when a current flows through the first coil 8C and the second coil 9C. Accordingly, the withstand voltage of the multilayer coil component 1C can be improved.

In the multilayer coil component 1C according to the present embodiment, the winding direction of the first coil 8C and the winding direction of the second coil 9C are opposite when viewed from the first direction D1. In this configuration, the magnetic flux generated by the first coil 8C and the magnetic flux generated by the second coil 9C cancel each other out. Accordingly, magnetic saturation can be suppressed, and thus direct current superimposition characteristics can be improved.

In the multilayer coil component 1C according to the present embodiment, the plurality of first coil conductors 60, 61, 62, 63, 64, and 65 of the first coil 8C and the plurality of second coil conductors 70, 71, 72, 73, 74, and 75 of the second coil 9C are equal in number. In this configuration, the magnetic flux generated by the first coil 8C and the magnetic flux generated by the second coil 9C can be effectively offset. Accordingly, magnetic saturation can be suppressed more effectively, and thus direct current superimposition characteristics can be improved.

In the multilayer coil component 1C, the element body 2B may have the magnetic body layer 7 (high-resistance layer) as in the case of the multilayer coil component 1 or the high-resistance portion 40 may be disposed in the element body 2B as in the case of the multilayer coil component 1A.

14

Although embodiments of the present invention have been described above, the present invention is not necessarily limited to the above embodiments and various modifications can be made without departing from the gist thereof.

5 The number of first coil conductors and the number of second coil conductors are not limited to the values described above. In the case of a configuration in which the winding direction of the first coil 8C and the winding direction of the second coil 9C are opposite and the orientations of the magnetic fluxes are different as in the multilayer coil component 1B of the fourth embodiment, the number of first coil conductors and the number of second coil conductors are preferably the same.

In the multilayer coil component 1, the distance in the first 15 direction D1 between the first coil 8 and the second coil 9C may be increased from the viewpoint of withstand voltage improvement. The same applies to the multilayer coil component 1A, the multilayer coil component 1B, and the multilayer coil component 1C.

20 The first external electrode 4 may have only the first electrode part 4a or only the second electrode part 4b. Likewise, the second external electrode 5 may have only the first electrode part 5a or only the second electrode part 5b. Various shapes can be adopted for the first external electrode 4 and the second external electrode 5.

What is claimed is:

1. A multilayer coil component comprising:
an element body formed by stacking a magnetic body layer containing a plurality of metal magnetic particles of a soft magnetic material;

30 a first coil disposed in the element body and configured to include a plurality of first coil conductors;
a second coil disposed in the element body and configured to include a plurality of second coil conductors;
a first external electrode to which one end portion of each of the first coil and the second coil is connected; and a second external electrode to which the other end portion of each of the first coil and the second coil is connected, wherein

40 the first coil and the second coil are separated from each other in a stacking direction of the magnetic body layer in the element body, and

between the first coil and the second coil of the element body, at least a region where the first coil and the second coil overlap when viewed from the stacking direction is higher in electrical resistivity than the magnetic body layer.

45 2. The multilayer coil component according to claim 1, wherein a high-resistance portion having a width dimension equal to or greater than width dimensions of the first coil conductor and the second coil conductor and higher in electrical resistivity than the magnetic body layer is disposed in the region where the first coil and the second coil overlap when viewed from the stacking direction.

50 3. The multilayer coil component according to claim 1, wherein a high-resistance layer higher in electrical resistivity than the magnetic body layer is provided between the first coil and the second coil in the element body.

55 4. The multilayer coil component according to claim 1, wherein the first coil has a first connecting conductor connected to the first external electrode and a second connecting conductor connected to the second external electrode, the second coil has a third connecting conductor connected to the first external electrode and a fourth connecting conductor connected to the second external electrode,

15

a distance between the second connecting conductor and the fourth connecting conductor is shorter than a distance between the first connecting conductor and the third connecting conductor in the stacking direction of the magnetic body layer, and

a winding direction of the first coil and a winding direction of the second coil are the same when viewed from the stacking direction.

5. The multilayer coil component according to claim 1, wherein a plurality of metal magnetic particles are disposed along the stacking direction of the magnetic body layer between the first coil and the second coil.

6. A multilayer coil component comprising:

an element body formed by stacking a magnetic body layer containing a plurality of metal magnetic particles of a soft magnetic material;

a first coil disposed in the element body and configured to include a plurality of first coil conductors;

a second coil disposed in the element body and configured to include a plurality of second coil conductors;

a first external electrode to which one end portion of each of the first coil and the second coil is connected; and

a second external electrode to which the other end portion of each of the first coil and the second coil is connected, wherein

a conductor closest to the second coil in the first coil and a conductor closest to the first coil in the second coil do not overlap when viewed from the stacking direction of the magnetic body layer.

5

10

20

25

30

16

7. A multilayer coil component comprising: an element body formed by stacking a magnetic body layer containing a plurality of metal magnetic particles of a soft magnetic material;

a first coil disposed in the element body and configured to include a plurality of first coil conductors;

a second coil disposed in the element body and configured to include a plurality of second coil conductors;

a first external electrode to which one end portion of each of the first coil and the second coil is connected; and a second external electrode to which the other end portion of each of the first coil and the second coil is connected, wherein

the first coil has a first connecting conductor connected to the first external electrode and a second connecting conductor connected to the second external electrode, the second coil has a third connecting conductor connected to the first external electrode and a fourth connecting conductor connected to the second external electrode,

a distance between the second connecting conductor and the fourth connecting conductor is shorter than a distance between the first connecting conductor and the third connecting conductor in a stacking direction of the magnetic body layer, and

a winding direction of the first coil is opposite to a winding direction of the second coil when viewed from the stacking direction.

8. The multilayer coil component according to claim 7, wherein the number of the first coil conductors of the first coil is the same as the number of the second coil conductors of the second coil.
